Des. 234,038
Patented Jan. 7, 1975

234,038

HONEYCOMB CUTTER

Neil Price, Lunebank, 15 Church Brow,
Halton, Lancaster, England

Filed Mar. 28, 1973, Ser. No. 345,542

Term of patent 3½ years

Int. Cl. D7—04

U.S. Cl. D7—43

FIG. 4

FIG. 5

FIG. 1 is a front perspective view of a honeycomb cutter showing my new design;

FIG. 2 is a front elevational view thereof, the rear elevation view being identical therewith;

FIG. 3 is a right side elevation view thereof, the left side being identical therewith;

FIG. 4 is a sectional view taken on line 4—4 of FIG. 3; and

FIG. 5 is a bottom plan thereof.

I claim:

The ornamental design for a honeycomb cutter, as shown and described.
